COLLAPSIBLE DOLLY CART

John M. Zupancic, Box 317, Cecil, Pa.

Filed June 2, 1959, Ser. No. 56,179

Term of patent 14 years

(Cl. D14—3)

FIG. 1 is a top perspective view of a collapsible dolly cart showing my new design;

FIG. 2 is a bottom perspective view thereof taken from the opposite direction of FIG. 1, and

FIG. 3 is a sectional view taken along line III-III of FIG. 1.

I claim:

The ornamental design for a collapsible dolly cart, substantially as shown.
